CENTRALIZED TRAFFIC CONTROLLING
SYSTEM FOR RAILROADSWinfred T. Powell, Rochester, N. Y., assignor to
General Railway Signal Company, Rochester,
N. Y.

Application September 1, 1936, Serial No. 98,906

1 Claim. (Cl. 246—124)

This invention relates to railway centralized traffic control systems and more particularly to a communication means for such a system, whereby information may be transmitted to a remote point concerning the presence or absence of trains in a plurality of track sections over a minimum number of line circuits.

In centralized traffic control systems it is expedient to employ a minimum number of line wires extending from the control point to various distant locations, both because of the cost of line wire as well as the increased cost of maintenance of a larger number of wires over the considerable distances necessary to extend such circuits. It is found expedient in such systems to not only provide means for transferring information to the control point concerning the operated positions of the various devices, such as signals and switches, but also to transmit information concerning the presence or absence of trains in various track sections and consequently in systems requiring this information from a number of track sections considerable savings may be made by multiplying the use of the line circuits employed to transmit this information.

In view of the above and other considerations it is proposed to provide means for communicating information to a distant point regarding the presence or absence of trains in two adjacent track sections and to accomplish this transmission over a single line circuit.

Other objects, purposes and characteristic features of this invention will be in part apparent and in part obvious as the description of the invention progresses, during which reference will be made to the accompanying drawing which shows in a diagrammatic and conventional manner two systems for indicating at a distant point the condition of two adjacent track sections in accordance with this invention. In the drawing:

Fig. 1 diagrammatically illustrates one form of the invention.

Fig. 2 is a fragmentary view of a second form of the invention.

Referring to Fig. 1, the invention has been shown applied to a track layout A, comprising a stretch of main track and a turnout track which is connected to the main track by a switch TS. The section of track approaching the switch TS is shown divided into two adjacent track sections 1 and 2, with the respective track relays 1T and 2T arranged in a conventional manner to detect the presence of trains therein.

In the dispatcher's office, or the control point,

a miniature track diagram TD is provided, which diagrammatically illustrates the distant track layout A. The track diagram contains two miniature incandescent lamps or indicators 1TI and 2TI, which are arranged therein at positions so that they may be readily associated with the corresponding track sections 1 and 2.

Referring to the form of the invention shown in Fig. 1, the apparatus associated with the miniature track diagram TD includes in series a three-position polar line relay F and a neutral line relay MG. Relay F is designed so that its polar contact 3 will operate to either its right or left hand position when the line is weakly energized, but the neutral contact of relay MG will pick up only when the line is strongly energized. A polarized source of energy is shown at the track location as a split battery B and the symbols (+) and (—) are used to indicate opposite terminals of a local source of energy at the control office, which source has not been shown.

In describing the invention it will be considered that a train, approaching track layout A from the left, enters track section 1 thereby dropping the associated track relay 1T. Energy is now supplied over a normally deenergized line circuit to relays F and MG at the dispatcher's office through a circuit that may be traced from the positive terminal of battery B, back contact 5 of relay 1T, front contact 6 of relay 2T, resistance R, back contact 7 of relay 1T, line wire L, the winding of relay MG, the winding of relay F, common wire COM, to the mid terminal C, of battery B. The inclusion of resistance R in the line circuit just traced results in a relatively low positive energization of the line, that is, the energy flows from right to left through the windings of relays F and MG, with the result that relay F will be operated to close contact 3 to its left hand position and relay MG will not be picked up. An indication of the occupancy of section 1 is then displayed on the miniature track diagram by the energization of lamp 1TI through an obvious circuit that is closed at contact 3 of relay F in its left-hand position.

When the train in section 1 progresses to a point in which it is occupying section 2 as well as section 1, it is obvious that both track relays 1T and 2T will be dropped with the result that resistance R will be short-circuited and a relatively high degree of positive energization will be applied to line L which will maintain relay F positioned to the left for lighting lamp 1TI and relay MG will be picked up for lighting lamp 2TI. This circuit may be traced from the positive

terminal of battery B, back contact 5 of relay 1T, back contact 8 of relay 2T, line wire L, the winding of relay MG, the winding of relay F, common wire COM, to mid terminal C of battery B. The indicators 1TI and 2TI are energized through obvious circuits that are closed at contact 3 of relay F in its left-hand position and front contact 4 of relay MG respectively.

When the train leaves the track section with which relay 1T is associated, the picking up of this relay, with relay 2T down, will remove the short-circuit from resistance R and energize the line with a low degree of negative current, that is, the current will flow through the windings of relays MG and F in a direction from left to right. Relay MG now releases its armature and contact 3 of relay F is positioned to the right for extinguishing lamp 1TI and maintaining lamp 2TI lighted. This circuit may be traced from the negative terminal of battery B, front contact 7 of relay 1T, resistance R, back contact 6 of relay 2T, line wire L, windings of relays MG and F, common wire COM, to mid-terminal C of battery B. Indication lamp 2TI is now lighted through a circuit that includes contact 3 of relay F in its right-hand position.

When the train leaves the section with which relay 2T is associated, the picking up of this relay places the line circuit in its normal deenergized condition and lamps 1TI and 2TI at the control office are extinguished.

Inasmuch as the operation of the present system is not entirely symmetrical for traffic in either direction, it will now be considered that section 2T only is occupied by a train progressing from right to left over track layout A.

A train entering from the right and dropping relay 2T energizes the line with a low degree of negative current which positions relay F to the right for lighting lamp 2TI and relay MG does not pick up under this condition; and when the train progresses to a point in which it occupies section 1 and section 2 the dropping of relay 1T changes the line circuit from a low negative energization to a high positive energization because both relays 1T and 2T are down. This positions relay F to the left and picks up relay MG for lighting both lamps 1TI and 2TI all in a manner previously described.

This sequence of operation is different from that previously described inasmuch as, in the first case, the polarity on relays F and MG was not changed when the train moved from section 1 to a point where it occupied section 2 as well as section 1.

When the train leaves section 2 track relay 2T picks up and under this condition the line is energized with a low degree of positive current which causes relay MG to release its armature and positions relay F to the left for lighting lamp 1TI (and for extinguishing lamp 2TI), through the circuit previously described for a train moving into section 1 from the left.

When this train leaves the section with which relay 1T is associated, both relays 1T and 2T will be picked up for deenergizing the line circuit which is its normal condition.

Referring to Fig. 2, there is here shown a modified circuit arrangement for energizing the indication lamps 1TI¹ and 2TI¹ at the control point, in which a relay F¹ is employed, having a neutral contact 9 and a three position polar contact 3¹.

This relay F¹ is so designed that contacts 3¹ and 9 operate in a manner similar to contacts 3 and 4 of relays F and MG, in Fig. 1, therefore, only one relay is required at the control office for energizing the lamps 1TI¹ and 2TI¹, it being understood that the apparatus at track layout A functions as previously described.

In other words, the structure and winding of relay F¹ are so proportioned with respect to the voltage of battery B, the resistance of R and the line resistance that a low degree of line energization effects the actuation of contact 3¹ and not contact 9, while a high degree of line energization effects the actuation of both contacts 3¹ and 9. In brief, relay F¹ is of the marginal type with respect to the operation of its contact 9, and of the sensitive type with respect to the operation of its contact 3¹.

Communicating means for a railway traffic control system have thus been provided, in which information as to the occupied or unoccupied condition of either one or both of two track sections may be transmitted to a remote point over a single polarized line circuit without the employment of alternating current or the like. The track sections to be indicated need not be adjacent as shown herein, but in most cases, the apparatus along the trackway is so grouped that it is expedient to indicate adjacent sections over the same line circuit.

The above rather specific description of one form of the present invention is given solely by way of example and is not intended in any manner whatsoever in a limiting sense. It is also understood that various modifications, adaptations and alterations may be applied to meet the requirements of practice without in any manner departing from the spirit or scope of the present invention except as limited by the appended claim.

What I claim is:—

In a system for indicating traffic conditions, a normally deenergized line circuit connecting a central office and two distant track sections each provided with a track relay, a three position polar relay included in series in said line circuit at said office and responsive to the polarity of energization of said line circuit whenever it is energized, a marginal relay at said office included in series in said line circuit and responsive to a relatively high degree of energization and unresponsive to a relatively low degree of energization, a source of energy and a resistor associated with said distant track sections, circuit means including contacts of said track relays for connecting said source and said resistor in series to supply said line circuit with energy of said low degree of one polarity or the other in accordance with the dropped away condition of one or the other of said track relays or to supply said line circuit with energy of said high degree of said one polarity when both said track relays are dropped away, two indicators in said office, and circuit means including contacts of said polar and marginal relays for energizing one or the other of said indicators when said line circuit is energized to said relatively low degree with said one or said other polarity and for energizing both said indicators when said line circuit is energized to said relatively high degree.

WINFRED T. POWELL.
